UNITED STATES PATENT OFFICE

ISRAEL V. EDGERTON, OF CHICAGO, ILLINOIS, ASSIGNOR TO NORTH AMERICAN CAR CORPORATION, OF CHICAGO, ILLINOIS, A CORPORATION OF ILLINOIS

STOCK CAR

Application filed November 12, 1928. Serial No. 318,775.

This invention relates to railway cars designed for the transportation of live stock, and has reference more particularly to that class of stock cars which are employed for shipping the smaller animals, such as sheep, lambs, hogs, calves and the like, and, for the purpose of economizing space, are in some instances constructed to provide a plurality of superposed animal compartments, to each of a height to permit the animals to stand erect therein.

It has come to be recognized among raisers, shippers and packers of live stock that comfortable and humane transportation conditions not only accord with public sentiment and satisfy laws governing the shipment of live stock, but are profitable through the substantial reduction effected thereby in the loss by injury and death of animals in transit. With the foregoing in view, an important object of the present invention has been to provide a stock car that will not only effect a maximum utilization of the total interior space of the car for transportation purposes, but will provide greatly improved loading, housing, feeding and watering conditions, and will eliminate or greatly reduce the hazards and dangers of discomfort and injury to the stock while in transit, and eliminate the time, trouble and expense of unloading and reloading the stock in transit on long hauls.

Other important objects of the invention are to provide a stock car constructed on the broad principle at present used in poultry cars, of a center aisle and tiers of stock compartments on either side thereof, in combination with improved means for loading the entire car from either side thereof, directing the stock into the compartments at either side of the aisle at will; to provide a multiple compartment car of the type last above mentioned with a cross-over at each level from the compartment on one side to the opposite compartment, with loading and unloading doors on both sides of the car, so that the compartments on both sides can be loaded and unloaded through one door; and to provide, in association with such cross-overs, means for closing

the same so as to separate the compartments connected thereby.

Still other objects and attendant advantages of the invention will be apparent to persons skilled in the art as the same becomes better understood by reference to the following detailed description, taken in connection with the accompanying drawings, wherein I have illustrated one practical structural form of the invention as embodied in a stock car heretofore made and tested, and in which—

Fig. 1 is a diagrammatic plan section, showing the division of the interior space of the car;

Fig. 2 is a vertical longitudinal section through the loading and unloading end of the car, on the line 2—2 of Fig. 1;

Fig. 3 is a plan section, on the line 3—3 of Fig. 2;

Fig. 4 is a vertical transverse section through the loading and unloading end of the car, on the line 4—4 of Fig. 1;

Fig. 5 is a vertical transverse section through the intermediate portion of the car, on the line 5—5 of Fig. 1;

Fig. 6 is a detail vertical section on line 6—6 of Fig. 1, showing in elevation one of the compartment baffle gates;

Fig. 7 is a sectional detail of Fig. 6, looking in the direction of the arrows 7, 7;

Fig. 8 is a sectional detail of Fig. 6, looking in the direction of the arrows 8, 8;

Fig. 9 is a detail vertical section on line 9—9 of Fig. 2, through a shiftable gate bar in a front wall of a compartment;

Fig. 10 is an elevation of a fragment of a front wall of a compartment, showing an adjustable bar and keeper for preventing the escape of small animals into the aisle through a feed opening;

Fig. 11 is a vertical section on line 11—11 of Fig. 10;

Fig. 12 is a fragmentary elevation of a gate lock, viewed in the direction of the arrows 12, 12 of Fig. 2.

Referring first to Fig. 1, which is a diagram showing the division of the interior space of the car, A designates the side walls and B the end walls of the usual rectangular

lar car body, one of the end walls having a grated ventilating opening C with a sliding door D therefor. E designates a pair of longitudinal lattice-work partitions that 5 form the inner walls of longitudinal tiers of stock compartments designated by F, that extend along the opposite sides of the car. Between the walls E is a longitudinal aisle G, which at one end opens into a state room H at 10 one end of the car, and at its other end is terminated by a transverse portion I located a short distance inwardly of the end wall B. Opposed compartments F are adapted to 15 communicate with each other by a floor or platform K constituting a cross-over, this cross-over being located opposite and between the loading and unloading openings L in the side walls A; said openings being guarded by the usual sliding doors M. N 20 designates each of a pair of sliding gates which control communication of the cross-over K with the compartments F on either side thereof.

Referring now to the structural features of 25 the car more in detail, by reference to Fig. 5, it will be seen that on either side of the longitudinal aisle G are tiers of superposed compartments F; the floor 10 of the car forming the floor of the lowermost compartments, and the floors of the intermediate and top compartments being indicated at 11.

The inner vertical walls of the compartments, as best shown in Fig. 2, are of lattice-work form, comprising principally inner and outer groups of vertical bars 12 and 13, respectively, extending the full height of the three compartments and spaced sufficiently to accommodate horizontal bars 14 35 therebetween, this arrangement also being well shown in the cross-sectional view, Fig. 5. As herein shown, there are three (upper, intermediate, and lower) horizontal bars 14 in the front wall of each compartment, and 40 the horizontal and vertical bars are sufficiently spaced to provide feed openings between them.

The narrow transverse partition I which 45 bounds one end of the aisle G preferably comprises, as best shown in Fig. 4, a pair of spaced vertical bars 15 and cross bars 16 connecting the same substantially mid height of the several compartments. The vertical bars 15 are set inwardly sufficiently from the 50 vertical bars 12 to provide space for a pair of sliding gates 17 which control communication of the compartments on the outer sides thereof with the intermediate cross-over K. As shown in Fig. 4, upper and lower slide- 55 ways 18 and 19 are provided for the upper and lower edges of the gates 17. To open the gates, they are slid rearwardly into the aisle spaced, as illustrated in the case of the lowermost gate in Fig. 2; this being done 60 65 when loading the compartment with stock

through the door openings L, the animals first being directed across the cross-over K into the remote compartment until the latter is filled, the gates 17 then being closed, and the animals then being directed into the 70 near compartment until that is filled.

For feeding and watering the stock while in transit and without unloading, I provide in the center aisle, and disposed in front of the lower edge of each compartment, a plurality of feed troughs 20, which, as most clearly shown in Fig. 5, are removably supported in U-shaped hanger brackets 21 that are clipped onto the upper edge of the lowermost horizontal bar 14 of each compartment front wall. In connection with this particular bar 14, I desire to point out that it is disposed in lower-edge contact with the compartment floor 11, and the joint between the bar and the floor is filled with cement or other waterproof material, indicated at 22, for the purpose of forming a leak-proof joint, which effectively prevents water and dirt from the floor of the compartment leaking down into an underlying feed trough or onto the floor of the aisle. This is a feature of 80 large importance in point of sanitation and clean feeding.

The feed troughs 20 are designed mainly to accommodate drinking water and small feed such as grain. To provide for more bulky feed, such as hay, I equip the center aisle with a series of pivoted feed racks 23, of which several independent racks are provided lengthwise of each compartment except the lowermost, the floor of the aisle serving the purpose of the feed rack for the lowermost compartments. In the arrangement shown, the feed racks are pivoted at 24 to brackets 25 projecting into the aisle from the vertical posts 12, and, when in lowered position, are supported at their free edges by angle bar ledges 26 secured to the front wall of the opposite compartments. When not in use the feed racks are swung upwardly, as shown in the case of the topmost rack in Fig. 5, the free edge of the rack being held by a hinged keeper 27. Except at feeding time, all the racks are in upwardly folded position so as to permit unimpeded movement of the attendant through the longitudinal aisle from end to end of the compartments.

By reference to Fig. 4, it will be seen that the crossover K between opposed compartments is of sufficient width to permit the introduction of a pair of feed troughs thereon, said feed troughs lying in front of the sliding gates 17, which latter, when closed, provide feed openings through which the stock has access to the feed troughs. In this portion of the car the feed racks 23, of course, are not required, since hay can readily be supplied to the spaces between the gates 17, either with or without withdrawing the feed troughs 20. By reference to Fig. 5, it will 100 105 110 115 120 125 130 135 140 145 150

be noted that the feed racks 23 are slightly narrower than the aisle itself, but the edges of said racks overlap the inner edges of the underlying troughs 20, so that the racks and the troughs together, when arranged as shown, constitute an effective support for loose bulk feed such as hay and the like.

In Fig. 12, I show a simple form of lock for maintaining the gates 17 in closed position, the same consisting of latch bars 28 pivoted at 29 to the cross bar 16 of the end wall of the aisle and adapted to overlap the central horizontal bars of the gates 17 when the latter are closed. By merely swinging the latches upwardly to the dotted-line position shown in Fig. 12, the sliding gates are unlocked and may be moved out of the way to permit movement of the stock over the cross-over.

Where animals are loaded into a stock car, or a longitudinal compartment of a stock car, in a more or less crowded condition, serious injuries often occur through the sudden application of the brakes and the quick stopping of the car. To prevent this, it has heretofore been proposed to provide at short intervals baffle gates which can be locked in a position to separate the animals into small groups. My present invention contemplates the use of improved baffle gates which can be easily and quickly locked in service position, and as easily and quickly unlocked and swung out of service position to permit of full loading and unloading of the compartment. The details of this baffle gate are best shown in Figs. 6, 7 and 8, where it will be seen that the gate is a lattice structure consisting of intersecting vertical and horizontal bars 30 and 31, respectively, that are suspended by hinge straps 32 from a hinge rod 33 mounted in and crosswise of the roof of each compartment. Pivoted at 34 on the gate is a locking bar 35 which, when in locking position, is engaged at one end in a vertically slotted keeper 36 (Fig. 7) on the inner side of the front wall of the compartment, and at its other end by a vertically slotted keeper 37 on the inner side of the rear wall of the compartment. By reaching through the front wall and tilting the locking bar 35 to the dotted-line position shown in Fig. 6 the baffle gate is unlocked, and may then be swung upwardly to the full-line position shown in Fig. 8, wherein it is engaged and upheld by a suspension hook 38 hanging from the roof of the compartment. When the gate is lowered, the locking bar 35 is drawn down to horizontal position, its ends automatically entering the slotted keepers 36 and 37. This device constitutes a very simple, easily manipulated, and efficient baffle for dividing a compartment load of stock into smaller groups while in transit.

It is occasionally necessary to remove from a compartment sick or dead animals; and to

facilitate this I provide at suitable intervals lengthwise of the front wall of each compartment unloading spaces by a sufficiently wide spacing of adjacent vertical bars 13 and 12, as shown, for example, at the center of Fig. 2. To prevent the escape of live animals through such opening, I provide a shiftable guard bar 39, shown in detail in Figs. 2 and 9. This guard bar is of a height slightly less than the height of a compartment and is longitudinally slotted, as shown at 40, to engage with a bolt 41 mounted in one of the horizontal partition bars 14. The lower end of the guard bar 39 is normally engaged by a U-shaped keeper 42 that is secured to the bottom horizontal bar 14 of the compartment. By first lifting the bar 39 out of the keeper 42 and then swinging it sidewise to the position shown at the bottom of Fig. 2, a sufficiently large opening is presented for the removal of the sick or dead animal into the aisle.

The feed openings between the intermediate and lowermost horizontal bars 14 of each compartment are of a size to accommodate average or medium sized sheep, hogs and the like, but they may be large enough to permit the escape therethrough of small and under-sized animals, which occasionally get into a stock shipment. With a view to safeguarding against such a contingency, I preferably equip each compartment front wall with an auxiliary guard bar 43 somewhat narrower than the horizontal bars 14 and disposed between and in the vertical plane of the intermediate and lowermost bars 14. To support the auxiliary guard bar 43 I secure to certain of the vertical bars 13 supporting brackets 44, each provided with a lower seat 45 (Fig. 11) and an upper seat 46. The bar 43 normally occupies the upper seat 46, but when under-sized animals are found in the shipment, or when the entire shipment may consist of animals small enough to work through the feed openings, the bar 43 is shifted to the lower seats 45, thereby substantially reducing the height and area of the feed openings, and thus preventing the escape of the animals into the aisle. By locating the auxiliary guard bar 43 in the vertical plane of the horizontal compartment bars 14, aisle space is saved, since the auxiliary guard bar does not project into the aisle.

The topmost compartment of each tier is so high that it is not readily reached by an attendant standing on the floor of the aisle. To facilitate access by the attendant to the topmost compartments, I provide foot supports, which conveniently consist simply of bars 47 (Fig. 5) attached to the inner walls of the lowermost compartments on the aisle side of said walls. By standing on the bars 47, the attendant may readily reach the feed troughs and feed racks of the topmost compartments, as well as manipulate the ventilators in the

roof of the car and any other accessories located at relatively high points.

The manner in which the car is utilized for the humane and safe transportation of live stock has been to a considerable extent already indicated. Since loading doors are provided on both sides of the car, it makes no difference on which side the loading platform may be located. The side doors 20 having been opened, and the sliding gates controlling the cross-overs having been shifted into the aisle, the lowermost compartments are first filled by driving the animals first into the remote compartment and then into the near compartment, and then closing the sliding gates at the cross-over. Then, by means of elevated runways reaching to the levels of the second and third compartments, the latter are similarly filled. In unloading, the same operations are performed in the reverse order. The compartments are of ample height to permit the animals to stand erect so that they suffer no discomfort from being crowded into unnatural positions. The animals may be fed and watered at regular intervals while in transit without the trouble and delay of unloading on long hauls. Comparative tests with ordinary stock cars have demonstrated a reduction of approximately seventy per cent. of the shrinkage in weight of the stock during shipment.

I claim:

1. In a stock car, the combination with a car body having doors in its sides adjacent one end thereof, of tiers of compartments extending lengthwise of the sides of the car body and of a combined width less than the width of the car, and cross-overs connecting laterally opposite compartments between said doors, said compartments and cross-overs forming a longitudinal aisle of less length than the car.
2. In a stock car, the combination with a car body having doors in its sides adjacent one end thereof, of tiers of compartments extending lengthwise of the sides of the car body and of a combined width less than the width of the car, cross-overs connecting laterally opposite compartments between said doors, and gates guarding said cross-overs.

3. In a stock car, the combination with a car body having doors in its sides adjacent one end thereof, of tiers of compartments extending lengthwise of the sides of the car body and each of a width less than half the width of the car, thereby forming a center aisle between said tiers, cross-overs connecting laterally opposite compartments between said doors, and a pair of gates in each cross-over respectively controlling communication of the latter with the compartments on either side thereof.

4. In a stock car, the combination with a car body having doors in its sides adjacent one end thereof, of tiers of compartments ex-

tending lengthwise of the sides of the car body and each of a width less than half the width of the car, thereby forming a center aisle between said tiers, cross-overs connecting laterally opposite compartments between said doors, and sliding gates at the junctions of each cross-over with the compartments which it serves, said gates being slidable into said aisle to open them.

5. In a stock car, the combination with a car body having doors in its sides adjacent one end thereof, of tiers of compartments extending lengthwise of the sides of the car body and spaced to form a longitudinal aisle, cross-overs connecting laterally opposite compartments between said doors, sliding gates at the junctions of each cross-over with the compartments which it serves, said gates being slidable into said aisle to open them, and means for locking said gates in closed position.

6. In a stock car, the combination with a car body having oppositely located doors in its sides, of tiers of compartments extending lengthwise of the sides of the car body and spaced to form between them a longitudinal aisle, cross-overs connecting laterally opposite compartments between said doors, and a pair of gates in each cross-over respectively controlling communication of the latter with the compartments on either side thereof.

7. In a stock car, the combination with a car body having oppositely located doors in its sides, of tiers of compartments extending lengthwise of the sides of the car body and spaced to form between them a longitudinal aisle, cross-overs connecting laterally opposite compartments between said doors, fixed partitions between said cross-overs and said aisle, and a pair of gates in each cross-over respectively controlling communication of the latter with the compartments on either side thereof.

ISRAEL V. EDGERTON.
